[57] CLAIM

The ornamental design for a boat seat pedestal, as shown and described.

DESCRIPTION

FIG. 1 is a right side perspective view of a boat seat pedestal showing my new design;

FIG. 2 is a top plan view;

FIG. 3 is a right side elevational view;

FIG. 4 is a rear elevational view;

FIG. 5 is a left side elevational view; and

FIG. 6 is a front elevational view.

The undisclosed bottom surface is conventional in appearance.

FIG. 1

FIG. 2

FIG. 3

FIG. 4

FIG. 5

FIG. 6
